UNITED STATES PATENT OFFICE

2,608,292

DISPLAY PACKAGE FOR NECKTIES

William L. Stensgaard, Park Ridge, Ill., assignor to W. L. Stensgaard and Associates, Inc., a corporation of Illinois

Application April 27, 1949, Serial No. 89,905

1 Claim. (Cl. 206—7)

1

This invention relates to a display package for neckties, and in particular it relates to a display package which may be formed from a single piece of cardboard and which may be used both as a display rack and as a necktie package.

The principal object of the invention is to provide a compact, inexpensive device for displaying a number of neckties, which may be folded to form a necktie package.

A further object is to provide an accordion folded device in which the neckties and the display surfaces are completely encircled by a cover member when the device is folded.

A further object is to provide a display device which, when folded, forms a shipping package in which the neckties are not crushed closely against each other.

The invention is illustrated in a preferred embodiment in the drawings in which: Fig. 1 is a fragmentary plan view of a cardboard blank from which the device is formed; Fig. 2 is a side elevation of said blank; Fig. 3 is a front elevation of the display package in display position with neckties in place; Fig. 4 is a top plan view similar to Fig. 3; Fig. 5 is a side elevation of the package in closed position; Fig. 6 is an end elevation of the package in closed position; Fig. 7 is a plan view of a necktie shaper member; Fig. 8 is a fragmentary rear elevation showing a single display panel, and illustrating one method of placing a necktie therein; Fig. 9 is similar to Fig. 8, and illustrates a different method of placing a necktie on a display panel; Fig. 10 is a section taken as indicated at 10—10 of Fig. 8; and Fig. 11 is a section taken as indicated at 11—11 of Fig. 9.

The device comprises a series of hingedly connected panels, each of which is provided with appropriate means to receive and hold a single necktie. The display panel sections may be zig-zag or accordion folded along their hinged connecting lines so as to stand upon a store counter with all the neckties visible for display purposes. Cover members are integrally connected to the series of hinged display panels, so that the entire display device may be folded with the display panels superposed upon one another, the cover panels wrapped thereabout and the entire package secured in some convenient fashion. Thus, the device serves the dual purpose of a display member and a shipping package. As will be observed in the detailed description which follows, the entire device may be blanked out of a single rectangular piece of cardboard or other sheet material.

2

Referring to the drawings in greater detail, and referring first to Fig. 1, a rectangular sheet of cardboard indicated generally at 10, provides a blank from which the display package may be formed. A transverse score line 11 spaced from one end of the cardboard blank forms one margin of a display panel section 12, and additional score lines 11 delineate additional display panels 12 which are identical with that first mentioned. As best seen in Figs. 3 and 4, there are preferably five such display panels, although it will be apparent from the description of the device that any number of panels may be formed and particularly any odd numbered plurality of panels. An odd number of panels is preferred so that none of the backs of the panels 12 will be visible when the assembled display package is on a store counter in display position. Adjacent display panels are separated by two score lines 11, the space between adjacent score lines forming spacing strips 13, the purpose of which will be more fully described hereafter.

Additional score lines 14 set off a series of sections 15, 16, 17, 18 and 19 which provide cover panels. The cover panel section 19 has formed in its end margin spaced tongues 20, 21 and 22 of conventional type which combine with slits 23, 24 and 25 to provide means by which the finished display package may be retained in its closed position.

Inasmuch as the display panel sections 12 are identical, only one will be described in detail. The display panel section 12 is cut adjacent one of its ends, as at 26 and 27, to form means providing a supporting edge upon which a folded necktie may be hung for display purposes. In the preferred form shown, 26 and 27 are spaced parallel U-shaped cuts which form a U-shaped hanger member 30. Score lines 28 and 29 extend across each arm of the hanger member 30 to permit said member to be bent, or hinged, on the display panel 12.

Spaced between the hanger member 30 and the more distant margin of the display panel 12 are a pair of spaced, generally parallel cuts 31 and 32 forming a necktie retaining strap 33 across the display panel 12. As seen in the drawings, the cuts 31 and 32 are preferably fluted or scrolled in order to provide a decorative strip upon which the name of the manufacturer or dealer, or other desired information may be imprinted.

Spaced pairs of substantially perpendicular cuts 34 and 35 flank the margins of the retainer strap 33 and the extremities of each pair are

connected by score lines designated respectively as 36 and 37. The cuts 34 and 35 and the score lines 36 and 37 form relief panels 38 and 39, which may be bent rearwardly so that the strap 33 lies substantially in the plane of the display panel 12 when a necktie is inserted therebehind.

Referring now to Figs. 3 and 4, the blank formed from the sheet of cardboard 10 is shown after it has been assembled into the display package, and the manner of displaying neckties therein is illustrated. As best seen in Fig. 4, the display panels 12 are accordion folded with respect to one another along the score lines 11 so that the display package may stand on one of its longitudinal edges to furnish a support for neckties. The hanger members 30 are bent forwardly along the score lines 28 and 29, and a necktie N, folded twice as it would be for insertion in a box may be hung over each hanger member 30.

The necktie may be hung entirely in front of the display panel 12, with two of its folds behind the hanger member 30, as shown in Figs. 8 and 10; or alternatively, it may be hung with only its free ends in front of the display panel 12 and with its folded center portion in back of the panel 12, as shown in Figs. 9 and 11. In the latter case, the hanger member may remain substantially in the plane of the display panel 12 and the broad tongue 40 between the U-shaped arms may bend slightly backward out of the plane of the display panel.

The lower end of the necktie is inserted behind the retainer strap 33, and the relief panels 38 and 39 will then bend rearwardly along the score lines 36 and 37, so as to permit the retainer strap 33 to lie substantially in the plane of the display panel 12.

As best seen in Fig. 4, when the display package is in its display position with the display panels 12 in open display relationship, the cover panel sections 15 to 19, inclusive, are placed in angular relationship with respect to one another by bending the sheet 10 along the several score lines 14. The cover panel sections thus may be readily disposed largely to the rear of the display panels 12 when the package is in display position, increasing the stability of the display by broadening the base upon which it rests.

As best seen in Figs. 5 and 6, when the display package is in its closed position, the display panels 12 are in superposed relationship and the spacing strips 11 assure that adjacent panels 12 will be spaced apart a sufficient distance to prevent crushing of the neckties against one another. The cover panel sections completely encircle the display panels when the package is closed, the cover panel 15 lying against the rear surface of the immediately adjacent panel 12, the cover panel 16 lying across the upright margins of the display panels 12 and against the surfaces of two of the spacing strips 13, the cover panel 17 lying over the surface of the outer display panel 12 (the one at the left hand side of the sheet in Fig. 4), the cover panel 18 occupying a position opposed to that of the cover panel 16 and the cover panel 19 lying against the surface

of the cover panel 15 to complete the package. The tabs 20, 21 and 22 are inserted respectively, into the slits 23, 24 and 25 to retain the package in its closed position.

In order to prevent sliding and wrinkling of the neckties on the display panels 12, it is preferred that a necktie shaper member 41, illustrated in Fig. 7, be inserted within each necktie. The shaper member is preferably a piece of cardboard of the same shape as the wide end of a fore-in-hand tie, and is long enough to extend within the necktie to the hanger member 30 and back beneath the retainer strap 33.

While I have shown and described certain embodiments of my invention, it will be understood that it is capable of many modifications. Changes, therefore, in the construction and arrangement may be made without departing from the spirit and scope of the invention as disclosed in the appended claim.

I claim:

A one-piece display package for neckties comprising: at least three necktie display panels, the length of said panels being more than one-quarter and substantially less than one-half the length of a necktie; a transverse, integral necktie retainer strap positioned below the center of each panel; means on each panel providing an edge over which a necktie may be hung, said means comprising an upright, shallow U-shaped hanger member adjacent the upper end of each display panel, each hanger member being cut out of the panel and hinged therefrom at the upper end of its spaced arms and being so positioned that a necktie folded in the center and hung on said edge has its free ends slightly above the bottom of the panel and its center fold below the retainer strap; a spacing strip between adjacent panels and hinged to both of them to permit the package to stand upright with the panels in open display position, or to be folded with the panels disposed in parallel, overlying, closed position, and cover means hingedly connected to the free edge of one of said display panels, said cover means having top and bottom panels to span the display panels and two side strips of a width at least equal to the thickness of the closed package so as to encircle it, and being provided with fastening means for restraining the package in its folded position, the top panel, a side strip, the bottom panel, a side strip and the fastening means being serially arranged in that order.

WILLIAM L. STENSGAARD.
